UNITED STATES PATENT OFFICE.

CHARLES E. ROGERS, OF COVINGTON, VIRGINIA.

LEGGING.

1,172,051.

Specification of Letters Patent. Patented Feb. 15, 1916.

Application filed April 17, 1915. Serial No. 22,040.

To all whom it may concern:

Be it known that I, CHARLES E. ROGERS, a citizen of the United States, and a resident of Covington, in the county of Alleghany and State of Virginia, have invented new and useful Improvements in Leggings, of which the following is a full, clear, and exact description.

This invention relates to leggings for military and other purposes, and has reference more particularly to a legging which comprises a body having an underlying and an overlying part, the parts having co-acting, locking members, both concealed by the overlying part.

The object of the invention is to provide a simple and effective legging which can be used by soldiers, equestrians, hunters and others, which is capable of all the uses to which leggings are ordinarily put, which is extremely strong and durable, which is light in weight, which can be inexpensively manufactured, and which can be easily manipulated, besides being comfortable when worn, and attractive in appearance.

The invention consists in the construction and combination of parts to be more fully described hereinafter and particularly set forth in the claim.

Reference is to be had to the accompanying drawings forming a part of this specification, in which similar characters of reference indicate corresponding parts in all the views, and in which—

Figure 1 is a side elevation of a legging constituting an embodiment of my invention and having a part broken away; Fig. 2 is a fragmentary elevation showing the co-acting locking members which are employed; Fig. 3 is a similar view showing the parts in different positions; Fig. 4 is an enlarged, transverse section on the line 4—4 of Fig. 3; and Fig. 5 is a similar view on the line 5—5 of Fig. 4.

Referring more particularly to the drawings, I have shown a legging or puttee of the conventional form, having a body 10, formed at the lower end, 11, to fit comfortably about the ankle, and at the rear, 12,

shaped to conform to the outline of the lower leg. At the side, the legging is open and has an underlying part 13 and an overlying part 14. At suitable points along the length of the open side I employ fastening devices 15, preferably three in number. The underlying part 13, of the legging, is pro-

vided at points corresponding to the location of the fastening devices, with inwardly extending edge recesses or slots 16. Each slot has associated therewith at the longitudinal edges, serrated strips or bars 17 secured in place by means of rivets 18, or in any other suitable manner. These strips may be fashioned from metal or any other material adapted for the purpose. Secured to the overlying part of the legging, adjacent to the slots 16, are spring keepers 19, consisting of elongated members each having at one end a laterally disposed or enlarged head 20. At the opposite end, the keeper is secured to the legging by means of rivets 21 or the like. The head 20, at the inner face is provided with teeth or serrations 22 adapted to engage the corresponding serrated members 17. It will be seen that the length of the spring keepers 19 is received in one of the slots 16, so that the head can engage at the strips 17 as clearly shown in Fig. 4. The normal resiliency of the keeper tends to maintain the parts in engagement so that the legging is closed.

Each securing member has associated therewith a releasing device. This comprises an eyelet or ferrule 23 located in an opening 24 of the overlapping part of the legging, over one of the slots 16 of the underlying part. The eyelet has an inwardly extending ring 25 formed integrally therewith, which at its inner edge has an inwardly disposed flange 26. A button 27 is movably mounted within the eyelet and has a laterally extended flange 28 and a stud 29 which extend through the ring into engagement with the spring keeper 19. A helical spring 30 is located within the ring and engages the flange 28 of the button and the flange 26 of the ring, thus tending normally to press the button outwardly, that is, away from the spring keeper. When it is desired to release the keeper it is merely necessary to press the button inwardly, against the tension of the spring 30, to force the keeper out of engagement with the serrated strips 17, so that the legging can be opened.

It will be readily seen that by providing the elongated strips 17, which may be engaged by the keepers at different points of their lengths, the legging can be adjusted to different dimensions and can be made to fit snugly and comfortably. It will be understood furthermore, that the co-acting

locking members, *i. e.*, the strips 17, and the keepers, are concealed by the overlapping part of the legging, and that from the outside nothing is visible but the releasing button 17 with its eyelet. This arrangement serves to enhance the appearance of the article materially.

Having thus described my invention, I claim as new, and desire to secure by Letters Patent:

A legging comprising a body having an underlying and an overlying part, said underlying part having an edge recess, a serrated member secured to said underlying part adjacent to said recess, a resilient member

secured to said overlying part and adapted to extend through said recess and having a head adapted to engage said serrated member, said overlying part having an opening over said resilient member, and a spring-pressed releasing button movably mounted in said opening and engaging said resilient member.

In testimony whereof I have signed my name to this specification in the presence of two subscribing witnesses.

CHARLES E. ROGERS.
